United States Patent

Des. 238,136
Patented Dec. 23, 1975

238,136
COASTER

Jerome Goldstein, 17 Rural Drive, and Abraham Goldstein, 205 Secor Road, both of Scarsdale, N.Y. 10583

Filed Feb. 15, 1974, Ser. No. 442,988

Term of patent 14 years

Int. Cl. D7—01

U.S. Cl. D7—45

FIG. 1 is a top plan view of a coaster showing my new design;

FIG. 2 is a bottom view;

FIG. 3 is a side elevation view taken from the right of FIG. 1;

FIG. 4 is a side elevation view taken from the left of FIG. 1; and

FIG. 5 is a front elevation.

We claim:

The ornamental design for a coaster, as shown.
